[57] CLAIM

The ornamental design for an extension ladder shelf, as
shown and described.

DESCRIPTION

FIG. 1 is a perspective view of an extension ladder shelf
showing my new design;

FIG. 2 is a side elevation taken generally from the
lower right quadrant of FIG. 1, which elevation is a
reverse mirror image of an elevation taken generally
from the upper left quadrant of FIG. 1;

FIG. 3 is a top plan view thereof;

FIG. 4 is a front elevation taken generally from the
lower left quadrant of FIG. 1;

FIG. 5 is a bottom plan view thereof;

FIG. 6 is a back elevation taken generally from the
upper right quadrant of FIG. 1.
